UNITED STATES PATENT OFFICE

HERMAN T. SUNDSTROM, OF HOUSTON, TEXAS

SLUG LEVER ATTACHMENT FOR TYPOGRAPHICAL MACHINES

Application filed March 3, 1930. Serial No. 432,597.

My invention relates to an improvement in means for operating the slug lever or type-setting machines such as linotype and inter-type machines. It is adapted particularly for linotype machines but will serve equally well on other makes of machines.

The duty of the slug lever on linotype machines is to move the slug laterally away from the discharge opening so as to provide room for the ejection of the next slug. This slug lever has been previously operated from what is called the justification rod on the present type of machine. A pin slidable in a support in the frame of the machine is moved laterally against the slug lever as the justification rod is moved up and down. The shavings of lead from the trimming of the slugs very often fall upon the operating pin of the slug lever and adhering thereto causes it to stick and fail to function properly. It thus interferes with the action of the justification lever and the space bars are sometimes bent or broken due to a failure of the machine to function properly due to the sticking of the operating pin for the slug lever.

It is an object of my invention to operate the slug lever entirely separate from the justification rods.

I contemplate actuating the slug lever by connection through the body of the machine with the ejection lever by a separate connection, thus leaving the justification rod free to operate without interference from the slug lever.

It is a further object of the invention to eliminate liability of sticking of the slug lever operating means by the provision of a sliding cam which may be housed in such manner as to be free of clogging, due to the particles of lead shavings falling therein.

I also desire to provide an adjustable contact with the slug lever so that it may be moved through various lengths of stroke thus adapting it to be used with different sizes of type ranging from five point to seventy-two point type.

In the drawings I have shown only the essential parts of the machine which serve to illustrate my device. In Fig. 1 I have shown a broken section of the base of the machine

with my invention placed thereon for operation.

Fig. 2 is a broken perspective detail illustrating the manner in which the slug lever is operated.

Fig. 3 is a broken detail in top plan view of the actuating cam and roller.

Fig. 4 is a detail in perspective illustrating the construction of the slug lever roller.

With reference particularly to Fig. 1, the base of the machine is shown somewhat diagrammatically at 1. It serves as a support for the operating parts of the machine. At the rear of the machine is a downwardly extending bracket 2 which has its forward end formed with an opening therein to receive a pivot pin 3 upon which the ejector lever 4 is mounted. The upper end of the ejection lever is formed with a handle 5 and a lateral bracket 6 with an opening 7 therein to receive the ejection link. On the arm of the lever is a laterally extending lug 8 which is the ordinary operation of the machine acts as an arm against which the operating cam may contact to move said lever on its pivot to return it to normal position after the slug of type has been ejected. I have employed this lug for another and additional purpose of operating the slug lever rod 9.

As the lever 4 is given a lateral movement frequently in the operation of the device through a small degree of movement, I allow for a slight movement without affect upon the rod. This is done by attaching a yoke 10 at the end of said lever 9 resting on the upper side of the lug 8 and having contact members 11 and 12 on each side of the cam 8. These contact members are struck by the cam in its movement beyond a certain range and this movement serves to actuate the rod 9.

Referring particularly to Fig. 2 it will be noted that the rod 9 projects through the forward side of the machine and slides within an approximately U-shaped bracket 13. Said bracket 13 is connected to a supporting member 14 mounted on the frame of the machine by means of a cap screw 15. The member 14 is a supporting bracket already on the frame of the machine and has upper and lower arms 16 and 17 respectively between which the

starting and stopping lever is ordinarily pivoted. The upper arm 16 serves as a support for the bracket 13 which I place on the machine and secure in position as stated.

5 The two arms of the yoke or bracket 13 have openings therethrough to receive the lever 9, which is slidable therein. The forward end of said lever 9 is beveled to form a cam face 18, as shown in Fig. 3. This cam face is made wider than the rod by forming a head 19 on said lever. The said lever is provided with a shock absorbing spring 20 which surrounds the lever 9 and bears at one end against the inner arm of the yoke or bracket and at its outer end said spring bears against the head 19 of the lever.

10 The slug lever is shown at 21. It is pivoted at its lower end upon a shaft 22 secured at 23 to the frame of the machine. It is adapted to be swung laterally to push the slug of type away from the ejection opening. A hand 23 at the upper end is provided to contact with the slugs of type and move them away from the opening. This arm is moved laterally to move said slugs by means of a roller 24 adapted to contact with the cam face 18 upon the slug lever operating rod. Said roller 24 is mounted rotatably upon a pin 25, which is adapted to be inserted through a slot 26 in an arm 27 and secured in position by a clamping nut 28. It will be seen that the roller may be adjusted to different positions in the slot 26 to allow for different lengths of movement of the slug lever.

15 The arm 27 is secured at its lower end upon the slug lever and midway of its length is secured at 30 to an arm 31 on said lever. The arm 31 is ordinarily upon the arm 21 and serves as a contact member for the push rod which ordinarily works the slug lever. It serves in my improvement as a support for the arm 27, which supports the roller 24. I also provide a stop pin 32 projecting laterally from the arm 27 to limit the inward movement of the slug lever. This pin is adapted to contact with the frame of the machine and is adjustable to allow the movement of the slug lever to the desired point.

20 In the operation of this device the cam mechanism, which ordinarily operates the ejector lever 4, will, in its movement, throw the ejector lever forward so as to push the operating rod forward, moving the cam face 18 of the rod against the roller 24 and moving the slug lever laterally to allow the ejection of the slug of type. The lever 4 is then moved in an opposite direction and the withdrawal of the operating rod 9 allows the slug lever to move inwardly and engage the slug and move it away from the ejection orifice. This movement of the slug lever is accomplished through a spring engaging with the hook 23 upon the slug lever in the usual manner. No change is made in the construction of the means for moving the slug lever toward the slug.

25 The advantages of this construction over the previous means for operating the slug lever lie in the fact that the operation thereof is removed from any connection with the justification rod. The old means of operating the slug lever was liable to stick and interfere materially with the ejector mechanism and the justification rod. As my device is connected simply with the ejection lever in the manner stated, no interference whatever with the other operating parts of the machine is experienced. Furthermore, with my improvement the degree of movement of the slug lever may easily be varied by adjusting the cam roller 24 in the slot 26, as previously noted. The device is, therefore, simple in construction and not liable to get out of order and eliminates interference with other parts of the machine previously experienced.

30 What I claim as new is:

1. In a type forming machine, a frame, an ejector lever pivoted thereon, a slug lever on said frame pivoted to swing in a plane perpendicular to that of said ejector lever, and means actuated by the movement of said ejector lever to move said slug lever.

2. In a type forming machine, a frame, an ejector lever pivoted thereon, a slug lever on said frame pivoted to swing in a plane perpendicular to that of said ejector lever and a slide rod on said ejector lever and actuated by the movement of said ejector lever to move said slug lever.

3. In a type forming machine, a frame, an ejector lever pivoted thereto on one side of said frame, a slug lever on the opposite side of said frame, a roller on said slug lever, a slide rod, a cam thereon adapted to contact with said roller and means on said ejector lever to move said slide rod.

4. In a type forming machine, a frame, an ejector lever pivoted thereto on one side of said frame, a slug lever on the opposite side of said frame, a roller on said slug lever, a slide rod, a cam thereon adapted to contact with said roller and a yoke on said slide rod adapted to be engaged by said ejector lever in its movement to force said cam against said roller.

5. In a type forming machine, a slug lever, an ejector lever, an arm on said slug lever, a slide-rod connected with said ejector lever, and means on said rod adapted to engage said arm swinging in a plane perpendicular thereto and move said slug lever.

6. In a type forming machine, a slug lever, an ejector lever, an arm on said slug lever, a slide rod connected with said ejector lever, a contact member on said arm, and a cam on said rod adapted to engage said contact member and move said slug lever.

7. A frame, an ejector lever pivoted thereon, a slug lever mounted opposite said ejector lever on said frame, a cam contacting mem-

ber on said slug lever, a slide rod loosely engaging said ejector lever, and a cam on said rod movable in response to the movement of said ejector lever to move said slug lever.

5 8. A frame, a slug lever pivoted thereon, a rod slideable at right angles to said slug lever, a cam roller on said slug lever, a cam on said rod to engage said roller and means to slide said rod and move said slug lever.

10 In testimony whereof I hereunto affix my signature this 28th day of February, A. D. 1930.

HERMAN T. SUNDSTROM.
